UNITED STATES PATENT OFFICE

JAMES RAMSEY SPEER, OF PITTSBURG, AND HENRY A. OTTO, OF ALLEGHENY, PENNSYLVANIA, ASSIGNORS, BY MESNE ASSIGNMENTS, TO THE MISSISSIPPI WIRE GLASS COMPANY, OF JERSEY CITY, NEW JERSEY, A CORPORATION OF NEW JERSEY.

GLASS-CASTING APPARATUS.

No. 813,675.

Specification of Letters Patent.

Patented Feb. 27, 1906.

Application filed April 9, 1903. Serial No. 151,848.

To all whom it may concern:

Be it known that we, JAMES RAMSEY SPEER, residing at Pittsburg, and HENRY A. OTTO, residing at Allegheny, in the county of Allegheny and State of Pennsylvania, citizens of the United States, have invented or discovered new and useful Improvements in Glass-Casting Apparatus, of which the following is a specification.

Referring to the drawings, Figure 1 is a plan view, partly in horizontal section and partly broken away, showing our invention; Fig. 2, a side elevation of the same; Fig. 3, a vertical section thereof; Fig. 4, a vertical cross-section of the casting-bed and contiguous parts, showing the means employed to adjust the bed vertically; and Fig. 5, a view showing the removable collars for the rolls.

Our invention relates to mechanism for making sheets of glass by rolling a pouring of glass between one or more rolls and a casting-bed.

The objects of our invention are to provide a novel means for cooling the casting-bed, to make the bed in sections so that damaged or undesirable parts may be cheaply replaced, and to so construct the bed and its carriage that the former may be vertically adjustable on the latter.

Further objects of our invention will appear in the detailed description immediately to follow.

We provide a pair of rails 1, forming a track on which wheels 2 of the carriage or car 3, supporting the casting-bed or table 4, travel back and forth beneath the roll 5, the roll preferably carrying at each end a sectional collar 5^a. This collar is made up of two arc-shaped sections which when united form an annulus or collar. The ends of the collar-sections are united by means of screws 5^b, which pass through overlapping tongues of the joints. Said screws are shown as passing radially through the collar and having the heads countersunk in the outer tongue of each joint, the outer end of the heads being flush with the surface of the collar.

The casting-bed 4 has upper and lower sections 6, provided with external casting-surfaces 7, which may have different characteristics. For example, one surface may be smooth and the other ribbed or otherwise fig-

ured to produce the surface configuration desired in the rolled sheets of glass. The contiguous surfaces 8 of the sections 6 have 55 grooves running longitudinally from end to end, and the grooves 9 are correspondingly located on each section, so that when the sections are brought together with the surfaces 8 contiguous longitudinal channels will result, as shown in Fig. 4. The ports or openings 10 at the ends of the grooves 9 are somewhat restricted, as shown, though this is not an essential feature. The two sections 6 of the bed 4 are fastened together by bolts or 65 screws 11. The bed is provided with end caps 12 and 13, each having a hollow or groove which with the ends of the bed form common chambers 14, communicating with the ports 10 of the grooves 9. 70

15 15 are tubes for conveying water from the chamber 14 in the caps 12, and 16 16 are tubes for conveying water into the chamber 14 in the caps 13. If desired, any other number of tubes 15 and 16 may be employed. 75 In fact, the tubes may connect directly with the ports 10.

The caps are secured to the bed by bolts 17. Extending outwardly from the face of each cap 12 and 13 is a lug or journal 18, having the head 19.

The screws 20 are threaded into holes 21 in the fixed nuts 22, secured in the sides of the car, and are preferably four in number, though a larger number may be used. These screws 85 bear at their upper ends against block 23, on which the bed 4 rests. The screws 20 in Fig. 2 appear far from the ends of the bed 4; but this is because a large portion of the bed has been omitted between the wheels 2, as shown. 90

24 designates one of the journal-boxes for a journal of the roll 5, as shown in Fig. 2. Two rods 25 pass loosely through the journal-blocks 24 and loosely through the cap 31 of the standard 32 and are connected at their 95 tops by the cross-plate 26, through which and the said cap 31 the screw 28 passes. The screw is operated by wheel 29 and carries at its lower end a plate 27, guided on the rods 25. A spring 30 is seated between the plate 100 27 and the journal-block 24. As these features do not form any part of the present invention, they need not be further described.

The carriage 3 is provided with lateral

racks 33, with which mesh the pinions 34, fast on the end portions of the roll 5.

It is found that when it is attempted to regulate the thickness of the glass sheets 5 solely by adjusting the roll 5 by means of the screws 28 the pinions 34 and racks 33 will fail to mesh when the sheets are made too thick. By making the adjustments wholly or in part by the operation of the screws 20 the glass 10 sheets may be made of any required thickness without the separation of the racks and pinions. Furthermore, the screws provide convenient and reliable means for making the bed absolutely level.

15 When the roll has been raised or the bed has been lowered to make adjustments for thicker or thinner sheets of glass, the collar 5 previously in use is removed and another one having the requisite thickness to fill the 20 space between the roll and the bed is substituted therefor. This is a particularly valuable feature, since the roll itself has on it the means for closing the end portions of the space between the bed and that part of the 25 roll which rolls the upper surface of the glass.

When it becomes desirable to use the lower casting-surface 7, hoisting devices, as the hooks of a traveling crane, are connected to the lugs 18 on the casting-bed and the latter 30 raised above the carriage 3. The bed is then rotated, the hooks acting as journal-bearings for the lugs 18, and again lowered upon the carriage.

Instead of raising the bed high enough above the car to allow the bed to be rotated 35 the bed may be slightly raised and the car run out from beneath the same. The bed may then be rotated, the car returned, and the bed lowered upon the car. It would be possible also to lower the car without raising 40 the bed, so that the bed could be rotated or the car removed from beneath it.

Having described our invention, we claim—

1. A fluid-cooled casting-bed having contiguous sections so constructed that, when 45 the sections are assembled open-ended parallel internal passages are thereby formed, channeled end sections bridging the ends of the passages, and inlet and outlet pipes connected respectively to the end sections. 50

2. In a glass-casting apparatus, a casting-bed having a plurality of separable external casting-surfaces, a support therefor during casting operations, and journals independent of the support, whereon the bed may after a casting operation be supported and rotated to bring a second casting-surface up- 55 permost.

Signed at Pittsburg this 3d day of April, 1903.

J. RAMSEY SPEER.
HENRY A. OTTO.
